UNITED STATES PATENT OFFICE.

JOHN DARLING, OF GLASGOW, SCOTLAND, WALTER G. BLOW, OF CARDIFF, ENGLAND, AND JOHN DARLING, JR., OF GLASGOW, SCOTLAND.

NEEDLE-THREADER.

SPECIFICATION forming part of Letters Patent No. 457,474, dated August 11, 1891.

Application filed June 20, 1891. Serial No. 396,918. (No model.)

To all whom it may concern:

Be it known that we, JOHN DARLING, engineer, residing at 64 Albert Road, Crosshill, Glasgow, in the county of Renfrew, Scotland, 5 ⁵⁵ WALTER GEORGE BLOW, gentleman, residing at Cardiff, Wales, England, and JOHN DARLING, Jr., warehouseman, residing at 64 Albert Road, Crosshill, Glasgow, Scotland, subjects of the Queen of Great Britain, have invented 10 a certain Improved Needle-Threader, of which the following is a specification.

The invention relates to an improved needle-threader, and has for its object to provide a device which will readily pass sewing-thread 15 through the eyes of ordinary hand-sewing needles.

According to this invention, when the needle is pushed into the apparatus a bar or the like pushes a loop of thread through the eye 20 of the needle, and then a retaining device retains the thread while the needle is withdrawn, so that the needle when withdrawn is threaded.

We will describe the invention with reference to the accompanying drawings, premis- 25 ing that we do not limit ourselves to the precise details which are illustrated.

Figure 1 is a front elevation. Fig. 2 is a longitudinal section showing the normal position. Fig. 3 is a longitudinal section showing 30 the loop of thread pushed through the eye of the needle. Fig. 4 shows the position when the needle is withdrawn after threading, and Fig. 5 is a plan.

A is a frame-work of suitable material— 35 such, for example, as metal—to the front part of the base-plate of which is pivoted a vertical arm or lever b, centered at b² and pressed outward by a spring b³, the upper end of the said lever working in a slot formed in the top 40 of the frame-work A. To the rear of the base-plate is centered or hinged at c² the needle-threading bar c, which extends upward, the point c³ thereof being inserted in a small slotted piece d, fitting so as to be capable of a 45 slight sliding movement in a slot in the upper end of the lever b. Above this slotted piece is a hole b⁴ in the lever b, in which slides the thread-retaining device consisting of the pin e, supported in the bracket f, attached to 50 the said lever b.

At some convenient part of the back of the

frame-work A a small hole or holes g is or are formed for the thread to pass through from a reel or bobbin H, the thread being then passed into the slot in the top of the vertical lever b. When it is desired to thread the needle, its eye end is pushed to the end of the groove in the top of the vertical lever b and presses or pushes in the upper end of the said lever, which turns on its center at b², this motion forcing the needle-threading bar c to also turn on its center c² and its upper end c³ to rise in the slotted piece d in the vertical lever b, and in its upward movement the upper end of the said needle-threading bar c pushes the 65 thread in the form of a loop through the eye of the needle, as shown in Fig. 3. The piece d is pressed upon by a spring d², which allows of the slight sliding movement of the said piece necessary to allow the upper end of the bar c to pass through the eyes of various descriptions of needles. As soon as the thread is pushed through the eye of the needle and as the vertical lever b returns under the action of the spring b³ the thread-retainer e 70 comes into position to pass through the loop formed. This is effected by means of a diagonal slot a³, formed in the top of the frame-work A, in which engages the bar e², secured to the pin e and sliding in a hole e³ in the lever b, so that when the vertical lever b is being pressed back by the sewing-needle this slot causes the pin e to be withdrawn to allow the upper end of the needle-threading bar c 75 to pass up with a loop of the thread, and as the vertical lever b returns the said diagonal slot a³ causes the pin e to move inward to engage with the loop of thread formed and hold the thread, so that when the needle is withdrawn, as shown in Fig. 4, it is threaded. 80

In the figures x represents the needles.

A needle-threader constructed as described may be made as a separate device, as shown; or it may be fixed to a lady's work box or table or be combined with a needle or cotton 95 case.

Having now particularly described and ascertained the nature of the said invention and in what manner the same is to be performed, we declare that what we claim is—

1. The combination of the lever having a suitable aperture for the introduction of a

needle and adapted to be moved thereby, and a threader-bar working in a slot in said lever and receiving motion therefrom, so that when the latter is moved in one direction the 5 threader will advance to thrust a thread through the eye of the needle, substantially as described.

2. The combination of a lever having a suitable aperture for the introduction of a needle, a threader-bar arranged to receive a forward thrust from said lever when the latter is moved in the proper direction and having its operative end guided in a slot of said lever transverse to the needle-aperture, and a 15 retaining-pin for catching the loop of thread thrust through the eye of the needle, substantially as described.

3. The combination of the lever having a suitable needle-aperture, a threader-bar 20 guided in and actuated by said lever so as to receive a forward thrust when the lever is pushed back, and an oscillating pin also actuated by said lever so as to advance across the needle-aperture and retain the loop of thread

when the threader-bar retreats, substantially 25 as described.

4. The combination of the lever, the head-piece adapted to receive the needle and capable of sliding on said lever, and the threader-bar guided in said adjustable head-piece and 30 reciprocated therein by the motions of said lever, substantially as described.

In testimony whereof we have signed our names to this specification in the presence of two subscribing witnesses.
